DESIGN FOR A TOY GUN

Jesse F. Thomas and Theodore B. Thomas,
New London, Wis.

Application November 26, 1943, Serial No. 111,795

Term of patent 3½ years

To all whom it may concern:

Be it known that we, Jesse F. Thomas and Theodore B. Thomas, citizens of the United States, residing at New London, in the county of Waupaca and State of Wisconsin, have invented a new, original, and ornamental Design for Toy Gun, of which the following is a specification, reference being had to the accompanying drawing, forming a part thereof.

In the drawing:

Figure 2 is a bottom plan view of the same; Figure 3 is a top plan view of the toy gun; and Figure 4 is a front end view of the same.

We claim:

The ornamental design for a toy gun, as shown.

JESSE F. THOMAS.
